US0D1111601S

(12) United States Design Patent (10) Patent No.: US D1,111,601 S
(45) Date of Patent: * Feb. 10, 2026

(54) RETAIL FIXTURE

- (71) Applicant: Apple Inc., Cupertino, CA (US)
- (72) Inventors: Evan M. Liao, Oakland, CA (US); Po Huang, Campbell, CA (US); Allison Inouye, San Francisco, CA (US); Jean-Marc Gady, Menlo Park, CA (US); Nicholas E. Corti, San Francisco, CA (US); Rimas K. Simaitis, Menlo Park, CA (US)
- (73) Assignee: Apple Inc., Cupertino, CA (US)
- () Term: 15 Years
- (21) Appl. No.: 29/918,946
- (22) Filed: Nov. 30, 2023
- (51) LOC (15) Cl. 06-04
- (52) U.S. Cl. USPC D6/672
- (58) Field of Classification Search
USPC D6/657, 671, 671.1, 672, 673, 675, D6/680.2, 681.2, 698, 699
CPC A47F 3/00; A47B 2009/006; A47B 55/00; A47B 67/04

CLAIM

The ornamental design for a retail fixture as shown and described.

DESCRIPTION

FIG. 1 is a top rear isometric view of a retail fixture showing the claimed design;

FIG. 2 is a top front isometric view thereof;

FIG. 3 is a rear elevation view thereof;

FIG. 4 is a front elevation view thereof;

FIG. 5 is a right side elevation view thereof;

FIG. 6 is a left side elevation view thereof;

FIG. 7 is a top plan view thereof;

FIG. 8 is a top rear isometric view of a retail fixture showing the claimed design;

FIG. 9 is a top front isometric view thereof;

FIG. 10 is a rear elevation view thereof;

FIG. 11 is a front elevation view thereof;

FIG. 12 is a right side elevation view thereof;

FIG. 13 is a left side elevation view thereof; and,

FIG. 14 is a top plan view thereof.

1 Claim, 12 Drawing Sheets
